AUTOMATIC SHEET FEEDING APPARATUS

Bruce Wale, Berkeley, Calif.

Application January 31, 1940, Serial No. 316,659

8 Claims. (Cl. 271—13)

This invention relates to sheet feeding apparatus and is more particularly concerned with apparatus for separating sheets of paper or like material from a pile and feeding them in regular order to a printing press or the like.

The invention, in its preferred embodiment to be hereinafter described, is especially adapted for continuously feeding sheets with adjacent ends lapped to the feeder heads described and claimed in my copending application Serial No. 197,738, filed March 23, 1938, but may be employed in connection with any sheet printing apparatus.

It is a major object of the invention to provide a novel sheet feeding apparatus wherein sheets of paper or like material are efficiently separated from a pile and successively fed in accurate and lapped relation toward a printing press or the like.

It is a further object of the invention to provide a sheet feed apparatus having arrangements for separating sheets of paper or the like from a pile and feeding them in lapped relation wherein novel adjustable mechanism for laterally registering the sheets during feeding is provided. Preferably this mechanism is reversible to register the sheets with either of a pair of side edge guides.

A further object of the invention is to provide novel sheet feeding apparatus and methods wherein sheets are continuously fed in lapped relation to a printing cylinder whose surface speed is substantially an even multiple of the feeding speed of the sheets. Preferably shorter sheets receiving only one impression from the cylinder are fed at a faster rate than longer sheets receiving two or more impressions from the cylinder.

A further object of the invention is to provide a sheet feeding apparatus having novel automatically operable arrangements for periodically restoring the top of a pile of sheets of paper or the like to a predetermined level during feeding operations. Preferably a manual control is also provided for the same purpose.

It is a further object of the invention to provide novel arrangements for separating a sheet from the top of a pile regardless of curls or distortions in the sheet wherein the sheet is subjected to blasts of air or like fluid along one or more edges in such a manner as to provide a lubricating and ventilating film between it and the next lowest sheet and thereby render it easily removable from the pile.

A further object of the invention is to provide

novel sheet feeding apparatus for feeding sheets continuously and in lapped relation from the top of a pile wherein a pneumatic sheet advancing device and nozzles supplying lubricating blasts of air for floating the top sheet of the pile are arranged to cooperate in a novel manner promoting high speed, accurately-timed feeding.

Further objects of the invention will presently appear as the description proceeds in connection with the appended claims and the annexed drawings wherein:

15 Figure 1 is a top plan view of the rear portion of the sheet feeding apparatus of the invention illustrating especially the platform upon which the sheets are piled, and associated structure.

16 Figure 2 is a top plan view of the front portion of the sheet feeding apparatus of the invention illustrating especially the feed table and registering apparatus.

20 Figure 3 is a side elevation of the sheet feeding apparatus of Figure 1.

21 Figure 4 is a side elevation of the sheet feeding apparatus of Figure 2.

22 Figure 4A is a front view of the brushing finger.

23 Figure 5 is a fragmentary enlarged plan view illustrating the feed wheel drive and the platform height control mechanism.

24 Figure 6 is a side elevation of the apparatus of Figure 5 illustrating mainly the ratchet mechanism for controlling the platform height.

25 Figure 7 is an end elevation of the apparatus of Figure 5 further illustrating the ratchet mechanism.

26 Figure 8 is a plan view of the floating air blast nozzle.

27 Figure 9 is a side elevation of the nozzle of Figure 8.

28 Figure 10 is an end view of the nozzle of Figures 8 and 9.

29 Briefly the invention comprises a feed table 11 arranged forwardly of an adjustable sheet pile platform 12 and adapted to convey sheets fed from the top of the pile, with their adjacent ends lapped, toward a printing couple consisting of a printing cylinder 13 and an impression cylinder 14.

30 For the sake of simplicity, the feeder head mechanism of said application is represented diagrammatically only in the present drawings by the stop 15 against which the forward edge of each sheet is finally positioned before entering the printing couple.

31 Platform 12 is provided with a smooth continuous floor made up of a series of contiguous

metal plates 16 having their polished upper surfaces lying in a single plane 17.

A plurality of upright flat stakes 18 arise in a row from the inner edge of platform 12 and terminate below the adjacent edge of table 11. A second row of similar flat stakes 19 arises from the side of platform 12 opposite the operator's side. Stakes 18 and 19 define the smooth sides of a right angled frame against which the front and side edges of the sheets are pushed as the operator piles them on the platform, so as to insure that the sheets are stacked in a uniform square pile.

The piled sheets rest on the rough upper surface of a plate 21 whose lower smooth side rests on surface 17. After the sheets have been piled in alignment in the corner formed by stakes 18 and 19, the pile is centered laterally of the platform by sliding plate 21 across surface 17. The rough upper surface of plate 21 prevents shifting of the pile relative to the plate during this operation.

Sprocket chains 22, 23, 24 and 25 have their lower ends secured to the four bottom corners of platform 12. Chains 22 and 23 pass upwardly and over toothed sprocket wheels 26 and 27, respectively, forwardly of the inner edge of the platform and beneath table 11. Sprocket wheels 22 and 23 are both rigid with a rotatable transverse shaft 28 supported in suitable brackets from table 11.

At the side opposite the operator, shaft 28 has secured thereto a worm gear 29 meshed with a worm 31 rigid with the forward end of a longitudinal shaft 32 which extends parallel to the platform. A second worm 33 is rigid with the rear end of shaft 32 and meshes with a worm gear 34 upon rotatable transverse shaft 35 which carries toothed sprocket wheels 36 and 37 over which the upper ends of sprocket chains 24 and 25, respectively, are passed.

A rotatable control shaft 38 having a manually operable handle 39 at the operator's end is provided at its inner end with a miter gear 41 meshed with a cooperating miter gear 42 on the adjacent end of shaft 32.

Upon rotation of shaft 38 by manipulation of handle 39, shafts 28 and 35 will be simultaneously rotated to vertically displace platform 12 by reason of the sprocket and chain support above-described.

An adjustable feeler finger 43, which rests on the top sheet of the pile on platform 12, is mounted at the end of an arm 44 pivoted at 45 intermediate its ends upon an arm 46 rigid with a stationary carriage casting 47. At its rear end arm 44 has secured thereto a resistance block 48 having an inclined bottom stop edge 49. Arm 44 is weighted on the feeler finger side of its pivot so as to normally lightly urge finger 43 into contact with the top sheet regardless of the level of the pile. Finger 43 can be adjusted during operation of the apparatus to control the level of the top of the sheet pile relative to the feed and other mechanism carried by carriage 47. When finger 43 is adjusted to a lower position, arm 44 will periodically restore the top of the pile to a corresponding low level as will later appear. When finger 43 is raised, a higher level can be maintained. This adjustment takes care of the requirements of various sheet materials with regard to suction and ventilation.

Casting 47 (Figure 6) is provided with a pair of spaced depending arms 51 and 52 formed with bosses for rotatably supporting shaft 32.

A ratchet wheel 53 having peripheral teeth 53' is keyed to shaft 32 in the space between arms 51 and 52 and is adapted to be driven by a pawl 54 pivotally mounted upon a rocker housing 55 upon shaft 32. Housing 55 has secured thereto an upwardly projecting post 61 having an inclined stop edge 62. Cam 50 is slidably keyed to power shaft 71 and rocks housing 55 by pressure against the flat lateral surface of post 61. Spring 56 urges housing 55 in a counterclockwise direction (Figure 7) to follow the periphery of cam 50 and is adjustably anchored at 57. Ratchet wheel 53 is slidable along shaft 32 when carriage 47 is shifted and is adapted to be rotated to raise platform 12 to bring the top of the pile to the level set by finger 43. Operative engagement of pawl 54 with wheel 53 is controlled by arm 44 in the following manner:

Cam 50 (Figure 7) is shown in full and dotted lines, respectively, to indicate the extreme inside and outside limits of the path of its periphery. Shaft 71 rotates once for each sheet fed. Hence, cam 50 will likewise rotate to rock post 61, which carries with it housing 55 and pawl 54. Rotation of cam 50 will rock post 61 to the extreme outside position (extreme left in Figure 7). As rotation progresses beyond the extreme outside position, post 61 will rock inwardly due to action of spring 56.

When the top of the sheet pile is at the desired level, block 48 arrests counterclockwise rocking of post 61 (Figure 7) and pawl 54 is prevented from slipping back far enough to engage a new tooth. Thus pawl 54 slides back and forth over the same tooth and ratchet 53 is not rotated.

When sufficient sheets have been fed from the pile to permit feeler 43 to assume a low level and rock arm 44 sufficiently, stop edge 49 will be raised enough to permit stop edge 62 to pass. The return swing on rock of post 61 will, therefore, continue to the lowest point of cam 50 as shown in solid lines in Figure 7. Post 61 having executed its maximum swing on rock, pawl 54 will move sufficiently to reach a new tooth of wheel 53. Rotation of cam 50 progressing, shaft 71 will provide the power to swing post 61 outwardly and thus raise platform 12 by virtue of the slight turning of shaft 32.

Rotation of cam 50 progressing for a new cycle, post 61 will be abruptly stopped in the position shown dotted in Figure 7. This stopping is occasioned by the fact that the pile has just been elevated and arm 44 has rocked to lower stop surface 49 into the path of stop surface 62. Hence pawl 54 again cannot reach a new tooth on wheel 53 because its return travel has been arrested and no raising of the platform 21 will occur. This cycle is repeated periodically as the sheets are fed to lower the level of the pile.

As has been stated, cam 50 rotates once for each sheet fed. By locating the sliding key 71' which drives cam 50 in a proper timing relation to the feed action, the abrupt stopping of post 61 will occur at the precise instant the top sheet has been fed from under feeler 43. Arm 44 will be firmly depressed on the feeler 43 end by this action and the sheets next succeeding, the top sheet will be clamped against movement or any tendency to follow the sheet being fed. By virtue of this same timing of cam 50 in relation to the feed of wheel 65, the pressure of feeler 43 on the now top sheet will be relieved by the outward swinging of post 61 at the pre-

cise instant the feed action of wheel 65 begins, thus assuring free withdrawal of said sheet from under feeler 43.

A locking pawl 63 is pivotally supported between the lower ends of arms 51 and 52 and is urged by spring 64 to normally bear in the teeth of ratchet wheel 53, thereby permitting rotation of the ratchet wheel in one direction only and maintaining the wheel against reverse rotation when pawl 54 is inactive.

A manually operable rod 60 enables the operator to lift pawl 54 when it is desired to raise or lower platform 12 by handle 39.

Carriage 46 also carries a rotary feed wheel assembly of the suction type indicated at 65 and 18 rotatably mounted at the outer end of a shaft 66 supported by a rigid elongated sleeve 67. At its inner end, shaft 66 carries a bevel gear 68 meshed with a bevel driving gear 69 slidably keyed upon an elongated drive shaft 71 which extends along the whole apparatus at the side opposite the operator.

Suction wheel assembly 65 is connected to a suitable exhaust source and functions to pick up the top sheet by suction and feeds it from the top of the pile toward table 11.

Suction wheel assembly 65 is similar to the usual rotary type employed in sheet feeding apparatus.

A bracket 160 is rigidly mounted on the end 30 of sleeve 67, being fixed thereto by screw 161. A stripper plate 162 is fixed to bracket 160 as by screws 163 toward the bottom level of wheels 65 which extend therethrough. Plate 162 serves as a surface to support sheets from above during the feeding operation of wheels 65.

Feed wheels 65 are in duplicate, having opposed axially extending, peripheral flanges 164, these flanges each having a series of radial perforations 165. A suction nozzle 166 is supported on plate 162 and projects between the wheels 65 and is provided between the wheels with lateral extensions 167 which fit the inner sides of the flanges 164 and have mouths with which the perforations 164 are adapted to register as the wheels 65 rotate.

The nozzle member 166 has a port 168 with which a suitable valve (not shown) cooperates. This valve is mounted on an arm 169 fixed to a short shaft 171 rotatable in bracket 160. Collars 172 locate shaft 171. A cam 173 has a high spot on its periphery and is fixed to rotate with shaft 66 and wheels 65. On rotation of cam 173, the high spot will lift arm 169 thus opening port 168 to the atmosphere and suction will not be applied to a sheet. As rotation progresses, arm 169 will sink, thus closing port 168 and suction from pipe 174 will be applied through the mouths of nozzle 166 against flanges 164, through perforations 165. The top sheet of the pile will thus be held to the lower surfaces of wheels 65 and propelled forwardly as they rotate. Pipe 174 is held in bracket 160 and extends to the outside of the machine where it is connected to a suitable suction pump (not shown).

Emphasis is placed on the novel location of the suction wheel assembly which is above the top sheet of the pile adjacent its rear edge adjacent feeler finger 43. The advantages of this location and the novel cooperation of the feeder wheels with other elements for advancing the top sheet will be later described in detail.

Casting 47 is supported for slidable movement parallel to shafts 32 and 71 so that finger 43 and feed wheel 65 may be located at any de-

sired position along the sheet and to accommodate for sheets of different length. This slidable adjustment of casting 47 is effected by rotation of knob 72 which carries at one end a gear 73 meshed with rack 74 rigid with the supporting frame of the apparatus.

Casting 47 carries an air blast nozzle member 75 floatingly mounted on a pipe 76 projecting from the casting. A second nozzle member 77, 10 employed especially for long sheets is located at the edge of the pile adjacent table 11.

Nozzle members 75 and 77 are identical in construction. Each comprises a 90° elbow 78 supported in loose threaded engagement upon the threaded terminal end of a horizontal air pressure supply pipe so as to be capable of free floating movement about the axis of the pipe. Nozzle 77 is supported on pipe 79.

The inner end of each nozzle member comprises an arcuate conduit 81 having a closed end and a laterally projecting nozzle 82. A spring steel fin 83 is secured upon the nozzle with its inner projecting end bent downwardly to provide a top sheet bearing portion 84 lying in the path of the air blast issuing from nozzle 82.

A balance arm 85, provided with an adjustable weight 86, is rigid with elbow 78 for balancing and governing the floating action of the nozzle member. An adjustable stop 80, rigid with elbow 78 and adapted to engage the bottom of the horizontal pipe, limits rotation of the nozzle member in the direction of the pile of sheets.

Nozzle members 75 and 77 are located to direct blasts of air which will traverse the top 35 surface of the top sheet of the pile on platform 12 as well as provide a film of air beneath the top sheet and the next underlying sheet.

Nozzles 82 are floatingly carried at the pile edge by reason of support by fins 83 resting on 40 the top sheet of the pile. Thus nozzles 82 are always in operative position to ventilate the top sheet regardless of the presence of deep valleys or curls in the material due to humidity conditions. The action of the air blast through nozzles 82 raises the top several sheets of the pile. By their free floating ability nozzles 82 will follow, thus assuring a greater degree of air lubrication for the topmost sheet than the others.

In practical operation both nozzles 82 are usually in horizontal alignment and both cooperate to provide a lubricating air film beneath the top sheet which enables the top sheet to be easily separated from the one immediately beneath by the suction wheel regardless of curls or other 55 distortion. If desired, nozzle 77 may be dispensed with except where long sheets are being fed.

The upper surface of table 11 is smooth and slightly wider than the maximum width of sheet 60 designed to be handled by the apparatus. Table 11 is of sufficient length to easily accommodate a sheet of the maximum length for which the apparatus is designed and preferably has a length at least four times the circumference of the printing cylinder. Apparatus designed for handling 65 sheets of a maximum length of 34" has a table 38" long.

Spaced parallel endless flat feed belts 87 and 88 extend longitudinally of the table. Belt 87 comprises a horizontal portion 89 running substantially flush with the surface of table 11 and, at opposite ends of portion 89, passes downwardly over pulleys 91 and 92 through suitable apertures in the table surface. Belt 87, beneath the table, is looped over pulleys 93 and 94. Pulley 94 is mounted on one end of an arm 95 whose other

end is adjustably clamped upon a stub shaft 96. Arm 95 may be adjusted about the axis of shaft 96 to tighten belt 87.

Pulley 92 is rigid with a transverse shaft 97 which is driven from shaft 71 by means of meshed gears 98 and 99. The other pulleys 91, 93 and 94 are idly mounted.

Belt 88 is supported and driven identically with belt 87, having a horizontal portion 101 running flush with the table surface and supporting pulleys 102 and 103 at opposite ends of that portion. Pulley 103 is rigid with shaft 97.

If desired, the top of table 11 may be provided with suitable grooves for longitudinal recessing and guiding the belts.

At the forward end of table 11, a stationary transverse rod 104 spaced above the table surface has its opposite ends seated in sockets 105 and 106. A similar parallel rod 107 extends between sockets 108 and 109 at the rear edge of the table.

An arm 111 is pivotally mounted at one end on rod 107 and carries at its other end a roller 112 resting on the belt (or the intermediate sheet) above pulley 92. An elongated arm 113 is pivotally mounted on rod 107 beside arm 111 and has its forward end held in a latch 114 on rod 104. Arm 113 is sufficiently springy to permit the slight lateral bending necessary to slip it under latch 114.

Midway between its ends, arm 113 carries a slideable block 115 having a releasable adjustment screw 116. A lever 117 is pivotally mounted on block 115 and carries a freely rotatable roller 120 adapted to rest on belt 87 (or the intermediate sheet).

A freely rotatable roller 118, similar to roller 112, is mounted above the belt at pulley 103 and is carried at the free end of an arm 119 pivoted on rod 107. An arm 121, similar to arm 113, is pivotally mounted on rod 107 adjacent arm 119 and has its forward end secured in a latch 122 on rod 104. A roller 123 is mounted at the free end of a lever 124 pivoted upon a block 125 slidably adjustable along arm 121.

Rollers 112, 118, 120 and 123 all rest by gravity on the sheets passing therebeneath and provide sufficient pressure to insure positive advance of those sheets by the feed belts bearing on the bottom surfaces of the sheets.

At opposite sides table 11 is provided with parallel longitudinal edge guides 126 and 127, respectively, which rest flush on the table surface. Adjacent its opposite ends, guide 126 is releasably clamped to rods 104 and 107 at 128 and 129, respectively. Similarly the opposite ends of guide 127 are releasably clamped to rods 104 and 107 at 131 and 132, respectively. By releasing clamps 128, 129, 131 and 132, edge guides 126 and 127 may be adjusted to any desired location laterally of the table.

Above the table, a central longitudinal brush finger drive shaft 133 extends between adjustable eccentric bearing supports 134 and 135 mounted on rods 104 and 107, respectively. Bearing supports 134 and 135 are provided with surface formations 136 adapted to be engaged by suitable tools for rotative adjustment of the eccentric supports to displace shaft 133 toward and away from the table surface for a purpose to be later described.

A collar 137 rigid with shaft 133 prevents axial movement thereof in one direction, and socket 138 prevents axial displacement of the shaft in the other direction.

At its forward end shaft 133 passes through

the recessed coupling 139 which joins the opposed sections of rod 104 and has secured thereto, beyond rod 104, a cylindrical block 141. Block 141 is provided with a removable cap 142 which is secured thereto to clamp a register brush finger 143. Finger 143 is preferably made of tough rubber or some similar material which will not cut the paper and which has a high coefficient of friction.

Block 141 is secured non-rotatively to shaft 133 by a set screw 144 which may be released to adjust the brush finger along the shaft.

A second cylindrical block 145 carrying a flexible brush finger 146, similar to finger 143, is non-rotatably secured to shaft 133 adjacent its rear end as by set screw 147. Screw 147 may be released to permit shifting of finger 146 along shaft 133 in accordance with the length of the sheets being fed along the table.

Shaft 133 has fixed thereto, intermediate its ends, a bevel gear 148 meshing with a similar bevel gear 149 at the inner end of a transverse shaft 151 which is supported by a stationary frame bracket extension 152 and whose other end carries a bevel gear 153 adapted to be meshed by either of a pair of opposed bevel gears 154 and 155 slidably but non-rotatably mounted on drive shaft 71.

Engagement of either gear 154 and 155 with gear 153 will cause rotation of shaft 133 in opposite directions, and locking screws 156 and 157 are provided for locking gears 154 and 155, respectively, in driving or inoperative position.

Fingers 143 and 146 engage the top surfaces 35 of the sheets passing therebeneath and brush the sheets toward edge guides 126 or 127, depending on the direction of rotation of the fingers. The bearing support adjustments at 134 and 135 may be employed to vary the degree of contact between the fingers and the sheets according to the thickness and character of the sheet material and also vary the force with which the sheets are brushed toward the edge guides. This adjustment is of such small magnitude as not to interfere with the meshing of gears 148 and 149.

The above-described adjustments of fingers 143 and 146 longitudinally of shaft 133 insure that both fingers may be arranged to simultaneously engage the same sheet during feeding regardless of its length. Finger 146 may be located on the opposite side of gear 148 from that shown in the drawings.

Shaft 71 is driven by a drive shaft 158 extending from the printing press and to which it is connected by a variable speed transmission 159 which is operable for selection of the desired speeds for driving the sheet advancing mechanism. As shown in Figure 1, a longitudinal edge guide 161 is adjustably clamped at opposite ends on rod 107 and a transverse rod 163 rigidly supported in sockets 164 and 165 at the upper opposite rear corners of the loading platform. A short guide 162 clamped to rod 107 is disposed 60 at the forward end of the platform.

Operation

With platform 12 in its lowest position, the operator stacks sheets in a pile on the upper surface plate 21, pushing the sheets into the corner formed by stakes 18 and 19 to insure that they are piled uniformly and squarely one on top of the other. The pile of sheets is then centered laterally of the platform by sliding plate 21 over surface 17 as above-described. Edge guides 161

and 162 are then adjusted to lie along opposite edges of the pile just below the top sheets. Edge guides 126 and 127 are aligned at the same time.

Ordinarily the top level of the sheet pile is slightly below the top surface of table 11. This level can be preliminarily adjusted by manipulation of handle 39 to raise or lower platform 12 as above-described.

The top of the sheet pile is automatically and periodically (about every five minutes preferably but at different intervals depending on the feed speed and other factors) restored to a predetermined level by the above-described ratchet mechanism. This insures active and proper cooperation between the feed wheel assembly at all times.

With the sheets piled on the platform at the proper level, feeler finger 43 rests on the top sheet centrally of the pile but adjacent its rear end. Rotary feeder wheel assembly 65 is likewise supported adjacent the rear end of the pile adjacent finger 43. By rotation of knob 72, carriage 47 may be displaced along the rack to position the feeler finger and rotary feeder wheel in any desired longitudinal relation according to the length of the sheets to be fed.

Nozzle members 75 and 77 are floatingly carried by the pile due to support by fins 83 resting on the top of the pile and are both disposed at substantially the same level even with the top sheet of the pile and emit flat streams of air which are directed transversely of the pile. The nozzles are so located with respect to the top of the pile that several of the top sheets are ventilated by the air streams, but the top sheet is subjected to the major action of the streams which provide moving films of air above the top sheet and between it and the next underlying sheet.

The above-described arrangement substantially floats the top sheet on a lubricating air film and enables it to be separated from the underlying sheets and fed from the top of the pile with comparative ease and with timed accuracy.

Due to this manner of floating the top sheet and imparting and relieving pressure through feeder 43 by cam 50 and post 61, less energy is required for the feed wheel to lift it from the pile and feed it to table 11. In my apparatus, the rotary suction feed wheel may be rotated at considerably reduced speed and yet feed sheets at the same rate as when it is used at normal high speed in other sheet feeding machines. During practical tests I have discovered that greater accuracy of timing and register is obtained at such reduced speed.

Further, by rotating the feed wheel at its normal high speed in my apparatus I may feed sheets at about four times the rate possible in other apparatus employing the same feed wheel at that speed. Ordinarily slower speed feed wheels give more accurate feed control and timing. The speed of feeding of the sheets is selected in accordance with the peripheral speed of the printing surface. Usually longer sheets are fed at slower speeds because such promotes accuracy of timing and register. The sheet speeds are generally even multiples of the printing surface circumferential distance. For example, an 8½" sheet is fed toward an 8½" circumference printing cylinder at a speed equal to the cylinder surface speed while a 34" sheet is fed to that cylinder at about one fourth the cylinder surface speed.

Previously to my invention, it has not been considered possible or practical to automatically feed sheets by means of a suction wheel from a pile

with the trailing end of each sheet lapped over the leading end of the succeeding sheet. This has partly been due to the fact that the feed wheel and associated air nozzle arrangements of the prior art have been mainly located at the front edge of the pile where they interfere with such lapped feeding, since each top sheet has to be completely removed from the pile before the nozzle can separate the underlying sheet in such apparatus.

In my novel arrangements, location of the air nozzles along a side edge or edges of the sheet and positioning of the feed wheel above the rear of the pile combine to enable such lapped feeding.

15 It is only necessary to know the length of each sheet and the desired distance of overlap and then set the speed of the feed wheel accordingly.

The floating top sheet is advanced by the feed wheel to the belts 87, 88 and rollers 112, 118 on table 11.

20 As the rear edge of the top sheet passes from beneath it, finger 43 is actuated by the action of cam 50 and post 61 on arm 44 to momentarily clamp the underlying sheets of the pile, thereby insuring advancement of the top sheet only.

25 By the time the rear edge of the moving top sheet has advanced beyond suction wheels 65, the clamping pressure of finger 43 is released and nozzle 76 is delivering a lubricating stream of air upon the underlying sheet (to be the next top sheet). Operation of the feed wheel is timed to start advance of this underlying sheet at the moment the top and underlying sheets have their adjacent ends in the desired lapped arrangement.

30 By this time advance of the underlying sheet is started, the leading end of the top sheet is being frictionally advanced by belts 87 and 88 on table 11 and actually the top sheet imparts a slight forward drag aiding the feed wheel in advancing the underlying sheet. Rollers 112, 118, 123 and 124 resting on the sheets insure positive feed of the sheets by belts 87 and 88.

35 In continuously feeding sheets having lengths from 34" to 17" to a printing press, I have found it desirable to employ a lap about equal to the circumference of the printing cylinder (in this case about 8½"). For one impression sheets about 8½" long, I employ a lap of about 4¼".

40 In printing presses having intermittent feeder heads, I increase the lap distance to compensate for the increased number of printing cylinder revolutions per sheet length. For example, in feeding 34" long sheets where the continuously rotating printing surface measures 6½" circumferentially and requires 5 revolutions to pull the sheet through the couple (instead of using a continuous feeder head), I employ a lap increased ½ over the continuous feed lap, or about 10¼".

45 As above-described feeler finger 43 actuates automatic mechanism for raising platform 12 to compensate for removal of sheets from the top of the pile and maintain the top of the pile at a practically constant level so as to be subjected to the above-described feeding operations.

50 The sheets fed successively in lapped relation onto table 11 are conveyed therealong toward the printing press. In apparatus designed for 34" long sheets, I preferably employ a table about 38" long. As the successive sheets advance along table 11 and come to a halt with their leading edge against stop 15 (Figure 4) their trailing edges have passed beyond rollers 120 and 123 and they are brushed sidewise by fingers 143 and 146 against either of side edge

guides 126 or 127 so as to insure proper register when they pass into the feeder head.

The apparatus of the invention above-described is the only suction wheel apparatus of which I have knowledge that will automatically feed sheets from the top of a pile in accurate underlapped relation at a controlled timed rate, and advance them in proper register toward a printing press or the like.

The apparatus is adjustable and adaptable for handling sheets of widely different sizes and advancing them at practically any desired speed in accurate timed relation. At the same time, the sheets are handled faster and more accurately than is possible in other suction wheel sheet feeding apparatus used prior to the invention.

The invention may be embodied in other specific forms without departing from the spirit or essential characteristics thereof. The present embodiments are therefore to be considered in all respects as illustrative and not restrictive, the scope of the invention being indicated by the appended claims rather than by the foregoing description, and all changes which come within the meaning and range of equivalency of the claims are therefore intended to be embraced therein.

What is claimed and desired to be secured by United States Letters Patent is:

1. In a sheet feeding apparatus, a platform for supporting a pile of sheets, an air blast nozzle at one edge of said pile aligned with the top sheet and directed to deliver the blast transversely of said pile, a rotary suction feed wheel positioned for feeding sheets from the top of said pile rotatable on an axis extending longitudinally of the direction of the flow of air under pressure and a common support for said nozzle and feed wheel.

2. In a sheet feeding apparatus, an air blast nozzle member movably supported at one end and provided with an apertured nozzle at the other end, and a supporting fin projecting from said nozzle, the aperture being elongated and extended to deliver air along both sides of the fin.

3. In a sheet feeding apparatus, an air blast nozzle member movably supported at one end

and provided with an apertured nozzle at the other end and means supporting said nozzle in such a manner as to enable it to float with the top sheet of the pile as the sheet is raised by action of the air blast.

4. In a sheet feeding apparatus, a platform for supporting a pile of sheets, automatic means for vertically displacing said platform, a carriage slidably adjustably mounted at one side of said platform, an unbalanced arm controlling said automatic means resting at one end of the top sheet of said pile, an air blast nozzle aligned with the top sheet on said pile, and a rotary feed wheel positioned to feed sheets from the top of said pile, said arm, nozzle and feed wheel all being carried by said adjustable carriage.

5. In a sheet feeding apparatus, a feed table along which sheets are advanced in succession toward a printing press or the like, a longitudinal edge guide on said table and means rotatable on an axis parallel to the direction of the advance of the sheet for brushing said sheets into contact with said edge guide when said advance along the table is completed.

20 6. In a sheet feeding apparatus, a feed table along which sheets are advanced toward a printing press or the like, a pair of spaced parallel edge guides on said table and reversible means rotatable on an axis parallel to the direction of 30 advance of the sheet for urging and maintaining said sheets in register with either of said guides when said advance along the table is completed.

7. In a sheet feeding apparatus, a feed table 35 along which sheets are advanced toward a printing press or the like, a longitudinal edge guide on said table and a driven shaft, rotatable and a sheet engaging finger mounted on said shaft adapted to brush said sheets against said guide 40 when said advance along the table is completed said shaft being substantially parallel to the longitudinal edge of the guide.

8. In the sheet feeding apparatus recited in claim 7, eccentric means for adjusting said finger toward or away from the sheet.

BRUCE WALE.
